DESIGN FOR A CONTROL DEVICE FOR PHONOGRAPHS

Ray Patten, Wilton, Conn., assignor to Dictaphone Corporation, New York, N. Y., a corporation of New York

Application June 30, 1938, Serial No. 78,181

Term of patent 14 years

To all whom it may concern:

Be it known that I, Ray Patten, a citizen of the United States and a resident of the town of Wilton, county of Fairfield, and State of Connecticut, have invented a new, original, and ornamental Design for a Control Device for Phonographs, of which the following is a specification, reference being had to the accompanying drawing, forming part thereof.

Figure 1 is a perspective view of a control device for phonographs, showing my new design; and Figure 2 a rear elevation thereof.

I claim:

The ornamental design for a control device for phonographs, as shown.

RAY PATTEN.
